UNITED STATES PATENT OFFICE

DENNIS E. MARTIN, OF GLASSPORT, PENNSYLVANIA, ASSIGNOR TO UNITED STATES GLASS COMPANY, OF PITTSBURGH, PENNSYLVANIA, A CORPORATION OF PENNSYLVANIA

DESIGN FOR A GOBLET OR SIMILAR ARTICLE

Application filed January 20, 1933. Serial No. 46,892. Term of patent 7 years.

To all whom it may concern:

Be it known that I, DENNIS E. MARTIN, a citizen of the United States, residing at Glassport, in the county of Allegheny and State of Pennsylvania, have invented a new, original, and ornamental Design for Goblet or Similar Article, of which the following is a specification, reference being had to the accompanying drawing, forming part thereof.

The figure is a front elevation of a goblet showing my new design.

The dominant feature of the design is the ornamental etching which is placed on the article.

I claim:

The ornamental design for a goblet or similar article, substantially as shown and described.

DENNIS E. MARTIN.
